UNITED STATES PATENT OFFICE.

ELIJAH MISENER MIERS, OF WIARTON, ONTARIO, CANADA.

ICE-SKATE.

1,263,091.

Specification of Letters Patent. Patented Apr. 16, 1918.

Application filed July 26, 1917. Serial No. 182,955.

To all whom it may concern:

Be it known that I, ELIJAH MISENER MIERS, of the town of Wiarton, in the county of Bruce and Province of Ontario, 5 Dominion of Canada, have invented certain new and useful Improvements in Ice-Skates; and I hereby declare that the following is a full, clear, and exact description of the same.

10 My invention relates to improvements in ice-skates, its main object being to embody in the structure of the skate, a resilient function, whereby the jarring effect of the impact of the skate with the unyielding ice 15 surface is practically nullified.

Such improved construction has the beneficial effect of a shock absorber, which results in a marked conservation of the strength of the skater, and is, therefore, 20 productive of higher individual energy in maintaining speed and endurance, as the cushioning of the jarring impact largely tends to eliminate fatigue.

This beneficial effect is particularly advantageous in racing contests, where long or even short distances are to be covered, and the necessity of maintaining high speed is absolutely essential.

To these ends, my invention consists of a 30 spring skate, comprising a runner-blade, a central vertical supporting member, a spring extending the length of the runner-blade secured at its center to the central supporting member and having its ends bent 35 inwardly and over the main section of the spring, and sole and heel plates secured to the bent-over ends of the spring.

In the drawings:

Figure 1, is a side elevation of my im- 40 proved skate;

Figs. 2 and 3, are sectional details illustrating the formation of the central supporting member;

Fig. 4, is an end elevation of the runner- 45 blade; and,

Fig. 5, is an end elevation of the runner-blade in engagement with the bent end of the spring.

Referring to the drawings, 1 is the runner-blade of the skate, having upwardly- 50 extending end members 2, 2, carrying hinged arms 3, 3, each of which is provided

with the end cross-pin 4. The hinged arms 3, 3 are carried on the pins or pivots 3^a. The central vertical supporting member 5, 55 rising from the runner-blade 1, and forming an integral part thereof, is provided with the right-angled side flanges 6, 6, which may preferably be formed (as clearly shown in Figs. 2 and 3) by splitting the 60 central supporting member longitudinally and bending over the split sections at right-angles to the central supporting member. In lieu of this particular construction, small angle-plates might be utilized. 65

7 is a flat metal spring, the main portion of which extends the length of the runner-blade, its ends 8, 8 being bent inwardly and over the main section of the spring 7, which is riveted to the flanges 6, 6, of the 70 central supporting member 5.

The bends 9, 9, of the spring 7, are semi-circular in form, each bend 9 of the spring is formed with a slot 10 (see Fig. 5), through which the hinged arms 3 project, 75 to yieldingly maintain the fixed relation of the ends of the spring to the runner-blade, the cross-pins 4, at the ends of the hinged arms 3, lying across the slotted bends 9, and within the same, to prevent the inadvertent 80 disengagement of the extensions and spring. 11 is the sole plate and 12 the heel plate, both of which are riveted to the inwardly-bent ends 8, 8 of the spring 7.

In action, the bearing springs are depressed vertically, under the weight of the skater and the force of the impact, the hinged arms 3, 3, during the flexion of the springs, turning on their hinge pins or pivots 3^a, to guide the movement of the 90 bent ends 9.

Having thus fully described the nature of my invention, what I claim as new and desire to secure by Letters Patent, is:—

1. A spring skate comprising a runner-blade, a central vertical supporting member, a spring extending the length of the runner-blade, secured at its center to the central supporting member and having its ends bent inwardly and over the main section of the spring, and sole and heel plates secured to the bent-over ends of the spring. 100

2. A spring skate comprising a runner-blade, a central vertical supporting mem-

ber, and upwardly-extending hinged arms, a spring extending the length of the runner-blade, secured at its center to the central supporting member and having its ends 5 bent inwardly and over the main section of the spring and provided with slots in its bent ends to permit of the play of the

hinged arms, and sole and heel plates secured to the bent-over ends of the springs.

Wiarton, July, 1917.

ELIJAH MISENER MIERS.

Signed in the presence of—

S. B. CAMERON,

T. C. ALLAN.
